Patented Oct. 13, 1925.

UNITED STATES PATENT OFFICE.

HENRY NEWTON, OF DARLEY, NEAR DERBY, ENGLAND.

SHELL AND BOMB.

Application filed September 1, 1921. Serial No. 497,511.

To all whom it may concern:

Be it known that I, HENRY NEWTON, a subject of the King of Great Britain and Ireland, and residing at Mile Ash House, Darley, near Derby, in the county of Derby, England, have invented certain new and useful Improvements in Shells and Bombs (for which application has been made for Letters Patent and Letters Patent granted in Great Britain No. 17,871 of 1915, filed December 22nd, 1915), of which the following is a specification.

This invention relates to the manufacture of shells, bombs and other projectiles.

Such devices, whether cast or pressed, usually require to be fitted or provided with one or more parts that are to be accurately formed and positioned necessitating a considerable expenditure of time and money in machining to gauge and like operations.

It is the object of my invention to devise improvements in the manufacture of such devices which will enable the same to be rapidly and accurately turned out and at a much less cost than hitherto so that there will be an increase in output and a decrease in expenditure.

According to my invention I form those parts which require to be accurately made and positioned separately, and I arrange them in a chill or sand or other mould in the exact relative positions that they are to occupy and then cast or press the material of the shell or other projectile around or within such parts according as they are located internally or externally of the shell body.

The invention also consists in the forms of projectile hereinafter described.

The accompanying drawings illustrate, by way of example, two forms of projectiles constructed in accordance with my invention.

Figure 1 is a sectional elevation of a shell adapted for use, for example, with a trench mortar.

Figure 2 is an underneath plan of Figure 1.

Figure 3 is a section on the line A—B of Figure 1.

Figure 4 is a fragmentary view illustrating on a somewhat larger scale the lower end of the shell shown in Figure 1.

Figures 5 and 6 are respectively an elevation and a plan of a detail shown in Figure 4.

Figure 7 is a similar view to Figure 1

illustrating a slightly modified form of projectile in accordance with the invention.

In carrying my invention into effect as illustrated in Figures 1 to 6, I arrange in a chill or sand or other mould, (not shown), a ring *a* of accurate dimensions to accurately define the position of the shell to the mortar, a pressed or otherwise suitably formed ring *b* of suitable material and also accurately formed, an internally threaded tube or plug *c* to take the fuse, and tail fins or plates *d*, all these parts being accurately positioned in recesses or otherwise in the mould in relation to the shell body *e* which is then cast round or within the parts without disturbing their positions.

The tail fins, which may be of tinned sheet iron, tin-plate or other convenient material, may be arranged to be secured in position in any suitable manner, one convenient arrangement being illustrated in Figures 1 and 3, from which it will be seen that the fins have holes *f* punched or otherwise formed therein through which the metal of the shell body flows.

The space *g* between the tail fins may be filled with the propellant charge which may comprise gun-cotton yarn, and in proximity thereto I fit a cartridge or cap *h* filled or not, as desired, with a suitable powder or other charge to ignite the propellant or with additional propellant, or four compartments may be formed for the propellant by passing wire or wires or the like through the apertures *p* formed near the edge of each fin and the propellant may be housed within such compartments. The cartridge *h* is exploded by a striker pin *i* carried by a pressed metal cap *k* held in position by spring tongues *l* which are depressed as they pass the slot *m* in the fin and then, on continued rotation of the cap, spring up again and lock the cap in position.

Figure 7 is a view of a modified form of shell or mortar bomb adapted to be propelled by a cartridge in which any usual type of cartridge container *n*, preferably made as light as possible and formed from annealed brass tubing or other suitable material, is incorporated during the operation of casting or pressing the projectile, and in addition the head is provided with lugs *o* over which a pressed metal striker cap (not shown) is adapted to be mounted in such a manner as to be thereby held in position.

It will be clear that my invention may be

applied with equal effect and like advantage to the fitting of the projectiles with driving bands or other bearing surfaces, gas-checks or other accessory parts for projectiles intended either for smooth bore or rifled ordnance, and is not to be confined to the examples referred to above, and I may also vary the method of holding the same in position during the operation of manufacture in any manner that may be found most convenient.

In the case of cast-iron "stick" bombs, in order to provide surfaces of suitable metal which may rub on the mortar walls, driving bands and gas-checks, such as copper rings of round or oblong or any desirable section and even tinned sheet-iron rings, may be cast into the cast-iron tube or stick at intervals along its length, being thus embedded and placed accurately as required.

It will thus be understood that the expenditure of time and the labour of making an exact and true-fitting adaptation of such parts to the body of the bomb or shell is entirely obviated, it being sufficient that the parts in question shall be properly constructed for their own particular functions, for example, the driving bands must be a smooth and close fit to the barrel, and the fuse-tube and contained parts must be properly constructed for their own special duties. The positioning of the parts in proper relation to the axis of the projectile is entirely provided for by incorporating these parts with the body of the shell or bomb in the process of casting or pressing the latter as above described. Advantages accrue also due to the fact that cast iron shells during the process of cooling in chills become of close texture and as a result maximum missile value is secured, as the shell is not disintegrated in dust, and a maximum amount of energy is stored in each missile due to the extra strength of the cast iron so treated.

A further advantage of projectiles formed in accordance with my invention is that the construction adopted ensures the projectile always falling nose downwards so that a cheap and efficient form of percussion fuse may be employed.

Having now described my invention, what I claim as new and desire to secure by Letters Patent is:—

1. A method of manufacturing shells, bombs, and other projectiles which consists in forming tail fins of sheet metal, accurately locating said fins in a mould, and casting an iron body upon said fins.

2. A method of manufacturing shells, bombs, and other projectiles which consists in forming tail fins of sheet metal with perforations in their edges, accurately locating said fins in a mould, and casting an iron body upon said fins and in their perforations.

3. As an article of manufacture a projectile composed of a cast iron body with sheet metal tail fins secured in said body by the casting operation.

4. A method of manufacturing shells, bombs, and other projectiles consisting in separately forming and accurately locating in a mould a plurality of rings adapted to fit, and accurately to position the projectile in, the bore of a piece of ordnance and casting the body of the projectile within and upon said rings.

5. A projectile comprising a cast iron body, recessed sheet metal tail fins secured therein, driving bands secured therein, a propellant charge and means for detonating the same secured in the recess in said tail fins.

6. A projectile comprising a cast iron body, tail fins secured therein set at an angle, and means for retaining a propellant charge in the space between said fins.

7. A projectile comprising a cast metal body, sheet metal tail fins attached thereto adapted to receive a propellant charge and a detonator, and a striker cap retained in said fins in position to engage the detonator.

8. A projectile comprising a cast iron body, sheet metal tail fins fixed thereto and having a recess formed between their adjacent edges, a detonator secured in said recess and positioned by the fins, and a striker cap also secured in and positioned by said fins in co-operative relation with the detonator.

9. In a projectile for a trench mortar the combination with the shell of detonating means for a propellant charge carried by the shell, and a striker adapted to set off said detonating means secured upon said shell in operative relation to said detonating means.

10. In a projectile for a trench mortar the combination with the shell of a propellant charge carried thereby, a detonator also carried by the shell in proximity to said charge, and a striker secured upon said shell in operative relation with said detonator.

11. In a projectile for a trench mortar the combination with the shell, of a detonator, and a pressed metal striker having resilient edges positioning said striker with respect to said detonator.

12. A projectile comprising a body, tail fins secured therein set at an angle, and means for retaining a propellant charge between said fins.

13. A projectile comprising a cast iron body, and perforated sheet metal tail fins secured in said body by the casting operation, the cast metal penetrating into the perforations.

14. A projectile comprising a body, tail fins attached to said body at an angle to

each other and having a cut-away and recessed portion at the end of their line of intersection, and a striker adapted to spring into said recessed portion.

- 5 15. In a projectile the combination with a cartridge having a percussion cap secured therein of a separable striker engaging with said cartridge to position the striker relatively thereto, and a striker pin which
10 stands in operative relation to said cap when the striker is positioned upon the cartridge.

16. In a projectile the combination with a cartridge having a percussion cap secured therein of a separable stamped metal 15 striker comprising an annular part surrounding the rim of said cartridge and a striker pin having the same location relative to said annular portion that the percussion cap has relative to the cartridge 20 rim.

In testimony whereof I have signed my name to this specification.

HENRY NEWTON.
